(57) **CLAIM**

The ornamental design for an antivibration pedestal for a musical instrument, as shown and described.

DESCRIPTION

FIG. 1 is a perspective view of first embodiment of an antivibration pedestal for a musical instrument showing a of my new design;

FIG. 2 is a front view of FIG. 1;

FIG. 3 is a rear view of FIG. 1;

FIG. 4 is a left side view of FIG. 1, the right side view being a mirror image of the left side view;

FIG. 5 is a top view of FIG. 1, the bottom view being a mirror image of the top view;

FIG. 6 is a perspective view of the second embodiment of a antivibration pedestal for a musical instrument showing a of a my new design;

FIG. 7 is a front view of FIG. 6;

FIG. 8 is a rear view of FIG. 6;

FIG. 9 is a left side view of FIG. 6;

FIG. 10 is a right side view of FIG. 6; and,

FIG. 11 is a top view of the second embodiment, the bottom view being a mirror image of the top view.

The evenly-dashed broken lines in the drawings illustrate the portions of the antivibration pedestal for a musical instrument and form no part of the claimed design. The dash-dot-dash broken line in the drawings define the bounds of the claim and the entire area located within form no part thereof.

1 Claim, 7 Drawing Sheets
